UNITED STATES PATENT OFFICE.

GEORGE HERBERT WHITTINGHAM, OF NEW YORK, N. Y., ASSIGNOR, BY MESNE ASSIGNMENTS, TO THE AUTOMATIC SWITCH COMPANY, A CORPORATION OF NEW YORK.

MOTOR-REGULATOR.

No. 862,226.

Specification of Letters Patent.

Patented Aug. 6, 1907.

Application filed July 16, 1903. Serial No. 165,779.

To all whom it may concern:

Be it known that GEORGE HERBERT WHITTINGHAM, a citizen of the United States, residing at New York, in the county of New York and State of New York, has invented certain new and useful Improvements in Motor-Regulators, of which the following is a full, clear, and exact specification.

This invention relates to the regulation and control of electric motors, and its object is to provide suitable 10 electro-mechanical means for controlling and regulating the starting and operation of electric motors.

In carrying out my present invention, I make use of mechanical means for effecting the insertion and removal of suitable resistance in the armature and field circuits of the motor, and by electrical means, I control the operation of the aforesaid mechanical means. The electrical means are under the immediate control of the operator and may be located at a 15 distance from the motor, or the mechanical means, as for example, upon the car, in an elevator system. I am also able to provide for the safe and economical starting of motors and the nice regulations of the speed of the same, by means of apparatus which in the hands of ignorant or careless operators cannot be made to 20 operate in such manner as to cause damage to the motor.

The invention will be described more fully with reference to the form thereof illustrated in the accompanying drawing, in which 30 Figure 1 is a diagrammatic view of the various parts, and Fig. 2 is a detail.

In the drawing *a* represents the armature of the motor to be controlled, and *b* represents the field circuit of the motor; *d* represents the resistance in the armature circuit, and *e* a resistance in the field circuit. These resistances are controlled by the arms *f*, *g* through the respective rods *k*, *l*. The clutches are driven by any suitable power, or by the motor to be controlled, which is geared or belted to the driven 35 wheel *m* upon the shaft *n*, which shaft carries worm gears *o*, *p*, which drive the clutches *h* and *i*. This form of clutch mechanism for controlling the resistances is described in my patent No. 728,814. Obviously 40 any suitable mechanical means may be employed for the purpose in lieu of the specific means here described. The switch *q*, controlled by the operator may be of any convenient type and located according to individual conditions. In the drawings I have shown a convenient type comprising a shaft *r* carrying 45 the blades *s* and *t* and a segmental plate *u* suitably shaped to make contact with the proper contacts. The contact jaws for blades *s* and *t* are sufficiently long 50 to permit movement of the blades after contact has been made, and thus permit plate *u* to be operated. 55 The switch *q* may be located upon the car and the

shaft *r* turned by a suitable handle, or may be located in the elevator shaft and shaft *r* turned by an ordinary shipper rope connected with wheel *v*.

In the position shown in the drawing, the switch has been turned so that the blades *s* and *t* make contact with the armature terminals, the contact wheel *5* carried by shaft *r* is in contact with the contact *4*, and plate *u* connects all of the contacts 24, 25, 72 and 81. The motor when the switch is in this position will be running at full speed.

To start the motor the operator turns the switch so that blades *s* and *t* make contact with the armature terminals, contact wheel *5* with contact *4*, and the edge *w* of plate *u* connects contacts 24 and 25. This establishes the field circuit of the motor as follows: 70 From terminal 1, by binding post 2, wire 3, contacts 4 and 5, wire 6, binding post 7, wire 8, binding post 9, wires 10 and binding post 11, wire 12, coil 13, which operates clutch *h*, thence by wire 14, coil 15, of retaining magnet 16, wire 17, coil 18, which operates the 75 pivoted switch arm *w*, wire 19, binding post 20, wire 21, binding post 22, wire 23, to contacts 24 and 25, wire 26, binding post 27, and terminal 28. The closing of this circuit causes coil 18 to move the pivoted switch arm *w* into contact with contact 45 and thus establish 80 the field circuit as follows: From terminal 1 to binding post 11 as before, then by wire 29, switch arm *g*, resistance *e*, if any be in circuit, wire 30, contact 31, wire 32, contact 33, wire 34, field *B*, contact 36, wires 37, 39, contact 40, wire 41, contact 42, wire 43 to plate 44 upon 85 which the pivoted switch arm *w* is mounted, thence by a switch arm *w* to contact 45, wire 46, coil 47, which operates as a magnet to hold the switch arm *w* in contact with the contact 45, thence by wire 48 to binding post 49, and wire 50 to binding post 51, and by wire 90 26 and binding post 27 to the terminal 28. This establishes the field circuit of the motor at its full strength. At the same time, the armature circuit is established through a starting resistance as follows: From terminal 1 to binding post 11, as before, thence by resistance 95 arm *f* through the armature resistance *d* to wire 52, through binding post 53, wire 54, to binding post 55, wire 56 to bushing 57, carried by shaft *r*, switch blade *s* to contact 58, wire 59, to the armature terminal 60, through the armature to armature terminal 61, thence 100 by wire 62, to contact 63, and by blade *t* to the bushing 38, and thence by wires 39, 41, 43, blade 44, blade *w*, and wires 46, 48, 50 and binding post 51, to the terminal *w*. These circuits having been established the clutch *h* moves the resistance arm *f* over the resistance contacts *d* and automatically cuts out of the armature circuit a resistance therein and starts the motor automatically according to predetermined conditions. The motor having been started, its speed may be controlled by inserting resistance in the field circuit. 105 110

Any desired amount of the resistance may be inserted and left inserted, and the motor thereby maintained at any desired speed. To accomplish this, the shaft r , is turned so as to cause the edge u^2 of the blade u to make contact with the contact 72. This establishes a circuit through the magnetic device for holding the arm g , in any desired position. This device, as illustrated in the drawing, may consist of a simple magnet which, when energized, exerts a determined attraction 10 upon a proper bar g' carried by the resistance arm g . The magnet is not sufficiently strong to prevent the operation of the resistance arm by the electric clutch. This circuit is from binding post 11 by wires 29, 64, 65, magnet 66, wire 67, binding post 68, wire 69, binding 15 post 70, wire 71, to contact 72, thence to contact 25, wire 26 to binding post 27 and to terminal 28. As soon as the operator moves the switch so as to bring the edge u^3 of the blade u into engagement with the contact 81 he will establish the circuit through the clutch which 20 operates the resistance g to insert resistance in the field circuit. This clutch circuit is from binding post 11 by wires 29, 64, 73, to coil 74, which operates the clutch 1, wire 75, retaining magnet 76, wire 77, binding post 78, binding post 79, wire 80, contact 81, and 25 thence by blade u to contact 25 and by wire 26 to binding post 27 and terminal 28. This clutch circuit having been established the clutch i operates to move resistance arm g to insert resistance in the field circuit of the motor, thus causing the speed of the motor to 30 increase as the resistance is inserted. The operator may maintain the speed of the motor constant by simply moving the switch so as to break contact between the edge u^3 and contact 81 which breaks the circuit of the clutch i , whereupon the magnet 66, which attracts 35 the proper plates g' , prevents further movement of the resistance arm g . The resistance e may be cut out by moving the switch so as to break contact between the edge u^2 and contact 72 whereupon the circuit of magnet 66 is broken and the resistance arm g is permitted to 40 drop back to its normal position. Likewise the resistance d may be inserted in the armature circuit by moving the switch so as to cause edge u' to break contact with contacts 24 and 25. When this occurs the motor will stop. The motor may be reversed by turning 45 the switch in the opposite direction, whereupon the same sequence of operations will ensue but the current will be introduced to the armature of the motor in the opposite direction.

It will be noted that by reason of the fact that driving 50 pulley m is belted directly to the armature of the motor to be regulated, a given rotation of the motor armature will effect a corresponding removal or insertion of resistances and the ratio of movement will always be the same when the respective circuits are made, and 55 moreover the ratio of gear o to gear p may be so determined, as shown in the drawing, as to cause the arm g to move over the resistance d more slowly than the arm g moves over resistance e , thereby increasing the armature current with the requisite slowness while the motor is starting, with a full field, and permitting a more rapid variation of the field for speed regulation after the motor is started.

It will be understood that the invention may be modified in various respects without departing from

the invention, and I, therefore, do not limit myself to 65 the precise construction herein shown and described.

Having thus described my invention, I declare that what I claim as new and desire to secure by Letters Patent is:

1. The combination of mechanical means for controlling 70 the resistance in the armature circuit of a motor, mechanical means for controlling resistance in the field circuit and electrical means for controlling the operation of each of said mechanical means separately, substantially as described.

2. The combination of mechanical means for controlling 75 the resistance in the armature circuit of a motor, mechanical means for controlling resistance in the field circuit and electrical means adapted to separately cause said mechanical means to first remove resistance from the armature circuit and then insert resistance in the field circuit, substantially as described.

3. The combination of mechanical means for controlling 80 the resistance in the armature circuit of a motor, mechanical means for controlling resistance in the field circuit, and electrical means for controlling the operation of said mechanical means, said means being adapted to arrest the operation of said mechanical means without changing the amount of resistance already introduced or removed, substantially as described.

4. The combination of mechanical means for controlling 85 the resistance in the armature circuit of a motor, mechanical means for controlling resistance in the field circuit, electric circuits controlling the respective mechanical means, and a switch adapted to make the circuit controlling the armature controlling means, and to make and break the circuit controlling the field controlling means, without affecting the first circuit, substantially as described.

5. The combination with a motor, of an armature resistance normally in circuit and a field resistance normally out of circuit, mechanical means for removing and inserting said resistances, clutches for governing said means, electric circuits controlling said clutches, and means for controlling said circuits to operate said clutches 100 successively, whereby upon closing said circuits said mechanical means are caused to automatically remove resistance from the armature circuit and then insert resistance in the field circuit, substantially as described.

6. The combination with a motor, of means for starting 110 the motor with a strong field, means for increasing the armature current, means for weakening the field, means for causing successive operation of said means automatically and means for causing the variation of the armature and field circuits at different rates of speed, substantially as 115 described.

7. The combination with a motor, of mechanical means 120 for respectively varying the armature and field circuits thereof, electrical circuits adapted to affect the operation of said mechanical means and means for closing said circuits separately, substantially as described.

8. The combination with a motor, of mechanical means 125 for respectively varying the armature and field circuits thereof, said means operating at different rates of speed, and electrical means for effecting the successive operation of said mechanical means, substantially as described.

9. The combination with a motor, of means for regulating 130 the same, means for effecting the operation of said regulating means in proportion to the movement of the motor, and additional independent means capable of further regulating the speed of the motor and operable at the will of the operator, substantially as described.

10. The combination with a motor, of means for varying 135 the armature and field circuits, electric circuits respectively controlling said means, and a switch adapted to successively make said circuits, substantially as described.

11. The combination with a motor, of means for varying 140 the field and armature circuits thereof, the said means being actuated successively by the revolution of the motor, means whereby one of said means starts with the motor, and means whereby the other can be connected to be

- driven by the motor at the will of the operator, substantially as described.
12. The combination with a motor, of means for varying the field and armature circuits thereof, the said means being actuated successively by the revolution of the motor, and separate electrical means for controlling the operation of each of said first named means, substantially as described.
13. The combination with a motor, of means for varying the field and armature circuits thereof, the said means being actuated by the revolution of the motor, and electrical means for controlling the operation of said first named means to first increase the armature circuit and then weaken the field circuit, substantially as described.
- 10 14. The combination with a motor, of means for starting the motor with a strong field and weak armature current, means for increasing the armature current, and electrically
- controlled mechanically actuated means for then weakening the field to increase the speed, the field weakening means being capable of manual regulation to secure varying strengths of field, substantially as described. 20
15. The combination with a motor, of means for regulating the starting thereof in proportion to the movement of the armature, and means for then further regulating the speed of the motor, said means being actuated by the movement of the armature but manually controllable by electrical means to secure varying speeds, substantially as described. 25

In testimony whereof I affix my signature, in presence of two witnesses.

GEORGE HERBERT WHITTINGHAM.
